UNITED STATES PATENT OFFICE.

WILLIAM A. SCHULZ, OF NEW YORK, N. Y.

DESIGN FOR A ROLLING TOY.

Application filed March 20, 1924. Serial No. 9,009. Term of patent 3½ years.

To all whom it may concern:

Be it known that I, WILLIAM A. SCHULZ, a citizen of Germany, residing at New York, in the county and State of New York, have invented a new, original, and ornamental Design for a Rolling Toy, of which the following is a specification, reference being had to the accompanying drawing, forming part thereof.

The figure is a perspective view of my rolling toy, showing my design.

I claim:

The ornamental design for a rolling toy, as shown.

WILLIAM A. SCHULZ.
